UNITED STATES PATENT OFFICE

FREDERICK A. THOMANN, OF EAST MOLINE, ILLINOIS, ASSIGNOR TO DEERE & COMPANY, OF MOLINE, ILLINOIS, A CORPORATION OF ILLINOIS

MOLDING WHEEL HUBS

Application filed September 22, 1924. Serial No. 738,988.

My invention relates to metallic wheels, particularly to that type commonly used for agricultural mechanisms, and the object of my device is the production of a cast hub in which a certain part, ordinarily mounted on the hub after the latter is completed, is placed within the flask or mold from which it emerges as a fixed part of the cast hub.

Referring to the drawings in which similar numerals indicate identical parts—

Figure 1 is a longitudinal section of a flask illustrating my invention.

Figure 2 is a longitudinal section of a completed hub embodying my invention, and

Figure 3 is a sectional view on the line 3—3 of Figure 2, of a completed hub.

The flask is of a type known in the art and more fully illustrated and described in my co-pending application, of even date here-
20 with; it is metallic and is composed of interlocking parts 1 and 2 provided with a sprue hole or gate 3 for passage of the molten metal. Suitable openings in the parts 1 and 2 are provided for insertion of a core 4. The path
25 of the metal as it is poured in the flask is indicated by arrows in Figure 1.

It is evident that the result of using a metal flask, having its interior conformed to the shape of a hub, is a chilled and very hard cast-
30 ing, consequently to provide a threaded outer end to such a hub, for reception of a dust cap, a find it necessary to utilize a collar 5 which is inserted in the flask, before the latter is assembled, in that part in which the outer end
35 of a hub is formed, and fitting therein to prevent the molten metal from reaching the outer circumference of the collar which is threaded as shown in Figures 1 and 2; a part
40 of said circumference is not threaded, as at a, and projects into the larger portion of the flask so that the flowing metal will envelop it when a cast is made.

To prevent rotary movement of the collar 5 on the outer portion 7 of the cast hub, studs
45 6 are formed, preferably integral with the collar 5, and project from the inner circum-
ference of the collar to become embedded in the metal of the outer portion 7 of the hub, as shown in Figure 2. Longitudinal movement
50 of the collar 5 on the hub is prevented by ta-

pering, internally, the collar 5, the tapered part 8 flaring outwardly from the studs 6 to the outer end of the collar, so that the molten metal filling between the core 4 and the entire inner surface of the collar will form, within
55 the tapered portion of the collar, an expanded end to the cast hub, locking the collar against any possible longitudinal movement.

By the method of forming a chilled hub with a collar inserted in the flask before the
60 molten metal is poured and held securely as part of a completed hub, the collar being threaded externally, I have made it possible to cap the outer end of the hub, as shown in dotted lines in Figure 1, in an effective and
65 economical manner.

What I claim is—

1. The method of producing a hub having an exteriorly threaded collar at one end, said method consisting of forming said collar with
70 an interiorly tapered surface, providing a mold conforming to said hub and with a recess for said collar, placing the collar in said recess, placing a core in said mold extending through said collar leaving a space between
75 said core and collar, and filling said mold and space with molten metal.

2. The method of producing a hub having an exteriorly threaded collar at one end, said method consisting of forming said collar with
80 an interiorly tapered surface with projecting studs, providing a mold conforming to said hub and with a recess for said collar, placing the collar in said recess, placing a core in the
85 mold leaving a space between said core and collar, and filling said mold and space with molten metal.

FREDERICK A. THOMANN.
